UNITED STATES PATENT OFFICE.

JOHN WM. FRITCH AND DELIA E. HOOPES, OF WASHINGTON, DISTRICT OF COLUMBIA.

INDICATING DEVICE.

1,168,941.

Specification of Letters Patent.

Patented Jan. 18, 1916.

Application filed March 29, 1915. Serial No. 17,705.

To all whom it may concern:

Be it known that we, JOHN W. FRITCH and DELIA E. HOOPES, citizens of the United States, and residents of the city of Washington, in the District of Columbia, have invented certain new and useful Improvements in Indicating Devices, of which the following is a specification.

Our invention relates to improvements 10 in indicating devices, and it consists in the combinations, constructions, and arrangements herein described and claimed.

The invention is designed to be used in connection with other machines, such as 15 punching or tabulating machines, and the main object is to provide a device by means of which one can ascertain whether a certain key which he desires to operate has, as a matter of fact, really been operated.

20 A further object of our invention is to provide a device of the type described which may be used in connection with punching machines which are adapted to perforate cards, as for instance, in compiling data for 25 the census, and which will indicate whether or not such cards have been correctly perforated, or punched.

20 A further object of our invention is to provide a device which will indicate whether 30 a key of the machine which is associated with the indicating device, has been correctly operated, and which will display a corresponding number or character similar to the one carried by or associated with the 35 key of the punching machine or other similar device, said indicating device maintaining in position parts indicating a number of successive operations so that one may at a glance see whether or not he has performed 40 several successive operations correctly.

A further object of our invention is to provide a device of the type described in which the parts bearing the numbers indicating the successive operations are automatically reset without any further attention on the part of the operator.

50 A further object of our invention is to provide a device of the type described in which a series of traveling indicating units is provided, these units being moved forwardly in succession by electro-magnetic means, or other suitable means, and each unit bearing a series of movable members containing figures or other suitable characters, any one of which may be brought into 55 an indicating position.

A further object of our invention is to provide a device in which these units may be moved if desirable without displaying the indicating number or character. 60

Other objects and advantages will appear in the following specification, and the novel features of the invention will be particularly pointed out in the appended claims.

Our invention is illustrated in the accompanying drawings forming part of this application, in which—

Figure 1 is a sectional view through a portion of the device. Fig. 2 is a plan view of the device. Fig. 3 is a side view. Fig. 4 70 is an enlarged sectional view along the line 4—4 of Fig. 6. Fig. 5 is a detail plan view of a portion of the device. Fig. 6 is a section along the line 6—6 of Fig. 4. Fig. 7 is a diagrammatic view showing the electric 75 circuit which operates the magnet. Fig. 8 is a view similar to Fig. 7 showing the parts in another position, and Fig. 9 is a fragmentary plan view showing a card, the punching of which is indicated by the indicating device. 80

As stated before, this device may be used in connection with any machine having a key board and keys having movable stems. It is primarily designed to be used in connection with a tabulating machine, such as 85 those used in the census office for tabulating data of different kinds.

In order to give a clear idea of the use of the indicating device, we will briefly refer 90 to the parts of the tabulating device which are necessary to show the coöperation of the indicating device with the tabulating device or punching device.

In Fig. 9 we have shown a card 11 having 95 a series of horizontal rows of figures, these figures ranging from 0 to 9, the first row containing zeros, the second ones, etc. In the tabulating or punching machine, this card when inserted is propelled forward and 100 is designed to be punched in accordance with predetermined rules. It is very necessary that this punching be correctly done, and in certain of the machines there is no means of knowing whether the card has been correctly punched until it has passed out of the machine. Our invention is designed to obviate this uncertainty. In Fig. 1 we have shown diagrammatically the card 11 upon a support 12 having openings 13 arranged to 105 register with the numerals in the vertical columns on the card, for it will be observed 110

that while the card has horizontal rows, each row containing a series of similar numerals, it also has a series of vertical columns, each column containing numerals 5 from 0 to 9. At 14 we have shown keys, these keys bearing numerals 0 to 9 to correspond to those in the vertical columns on the card. The stems 14^a of the keys are shown as being directly above the card 11 in Fig. 1, so that when the keys are depressed, the stems will punch the card and pass through the supporting plate 12.

We have briefly described certain parts of the tabulating or punching machine, in order that we may show the use of the indicating device, but it will be understood that the illustration of the parts of the punching machine are purely diagrammatic and have only been described in order to show the 15 connection and the use of the indicating device.

The indicating device proper consists of a frame 15 mounted on a base 16, and other parts hereinafter enumerated. Pivoted 20 on the frame 15 is a series of levers, 0^a, 1^a, 2^a, up to 9^a inclusive, these levers being pivoted on fulcrums 0^b to 9^b inclusive. The ends of the levers are pivotally connected with the vertically extending stems 30 0^c to 9^c inclusive. These stems pass through the top of the frame 15 and, as has been stated before, terminate just underneath the ends of the stems 14^a of the keys 14. It will be noted that the fulcrums 1^b, 2^b, etc., are 35 arranged in such a position that all of the levers, which are of a common length, will be given the same movement when the stems are depressed a given distance, this distance being common for all the 40 stems. The opposite ends of the levers 9^a, 8^a, 7^a, etc., are pivotally connected to rods 9^d, 8^d, 7^d, etc., respectively. These rods 9^d, 8^d, 7^d, etc., pass through a guide member 17 secured to the bottoms of opposed 45 runways or tracks 18 and 19. The latter are carried at the tops of uprights 20.

Referring now particularly to Figs. 1 and 3, it will be seen that we have provided lower tracks or runways 18^a and 19^a 50 corresponding to the upper tracks 18 and 19. The upper and lower tracks on each side, such as the tracks 18 and 18^a, are connected by curved track members, such as those shown at 18^b, thus providing for continuous 55 runways. Arranged to travel in the opposed runways, is a series of units. A description of one of these units will suffice, since they are alike. On referring to Figs. 4, 5, and 6, it will be seen that each unit comprises a 60 substantially rectangular casing 21 which is provided at its ends with axles 22 provided with rollers 23, there being four of these axles to each unit, so that the unit itself in passing along a straight portion of the runway, such as that along the upper portion 65

of the track will maintain its position parallel with the track itself.

Each unit is provided with a series of movable plates 24, which are pivotally mounted on a common pivot rod 25 extending from end to end of the casing 21. The upper portion of the casing is slotted, as shown at 26, to permit the pivoted plate 24 to swing outwardly into view, as shown in Fig. 6. Each of the plates is provided with 70 a spring 27 which is connected to a pin 27^x so as to hold the plate 24 in its upper position.

Associated with each of the plates 24 is a trip 28 which is pivotally mounted at 29 and 75 is normally held in engagement with the plate 24 by means of a spring 28^x. As will be seen from Fig. 6, the plate 24 bears two teeth or shoulders 24^a and 24^b respectively. These are adapted to be engaged by a 80 shoulder or hook 28^a of the member 28. In Fig. 6 we have shown the plate 24 at the right of the figure as being held in its normal position by means of the trip 28. These trips, as will be seen from Fig. 6, project 85 just below the bottom of the casing 21, and they are in alignment with the rods 0^d, 1^d, 2^d, etc. The plates 24 bear numerals from 0 to 9 which correspond with the numerals on the 90 keys shown in Fig. 2. The units are 95 designed to be moved so as to bring their respective plates 24 bearing the numerals from 0 to 9 just above these rods 0^d, 1^d, 2^d, etc. Now, when the key 5 for instance of the key 100 board shown in Fig. 2, is depressed, the lever 5^a will be operated so as to raise the rod 5^d, see Fig. 4, and the latter will come in contact with the trip 28 thus releasing the spring 105 pressed plate 24 and permitting the plate to fly upwardly through the slot 26 into the 110 view of the operator.

The means for causing the travel of the 115 unit around the endless runway is as follows: On referring to Figs. 3 and 6, it will be seen that each unit is provided with two downwardly extending teeth 21^x and 21^y. A pair of magnets 30 and 31 are carried by a 120 portion 32 of the frame. The magnet 30 has its armature 30^a on the end of a lever 33 which is pivoted at 34 and whose upper end bears a spring pressed pawl 35. The magnet 31 has an armature 31^a at the end of a lever 36 pivoted at 37 and bearing a spring 125 pressed pawl 38 at its upper end, similar to the pawl 35. Both of these spring pressed pawls are adapted to bear normally on the under side of the casings 21 of the units. It will be observed that the lever 36 bears a contact member 39 adapted to bridge the contacts 40 and 41 carried by the lever 33.

As will be seen from Figs. 1 and 4, each 130 of the levers 0^a, 1^a, etc., is provided with a pin 0^c, 1^c, etc., arranged to enter corresponding slots in a slidable member 42 which is 135 guided at its upper end by an extension of

the member 17 and at its lower end by a guide 43 carried by the partition 32. This 5 slideable member bears an insulating arm 44 arranged to close normally open spring contacts 45 and 46. This slideable member 42 as will be seen from the drawings, has its 10 row of slots arranged on an incline, that is to say, the row of slots is substantially parallel to the row of fulcrums 0^b, 1^b, 2^b, etc., and parallel to the ends of the lever 0^a, 1^a, 2^a, etc. The normal position of the pins 0^e, 1^e, 2^e, is that shown in Fig. 1, that is to say, the pins are at the bottom of the slots.

The electrical circuits that are used with 15 this device, will best be understood by an explanation of the operation of the device.

Let us assume that it is desired to punch a card like that shown at 11 in Fig. 9, and that the operator desires to punch the number 5 from the first vertical column at 20 the left. He presses downwardly on the key marked 5 in Fig. 2, thereby operating the lever 5^a, and raising the rod 5^d, see Fig. 4. The end of this rod engages the trip 28 so as to release the hook 28^a from the shoulder 24^b of the plate 24. The plate will 25 therefore be thrown upwardly by means of the spring 27, so as to display the number 5 and indicate to the operator that he has 30 correctly operated the device. If, for instance, he has operated 6 while intending to operate key 5, then the number 6 would appear, showing him instantly that there 35 was a mistake in punching the card and thereby giving him the opportunity to insert another card, without the necessity of punching all the data on the card and then finding that there was a mistake at the end of the operation. At the same time 40 that the lever 5^a moves the rod 5^d upwardly the pin 5^e on the lever 5^a engages the upper wall of the slot in the slideable member 42, thus raising this member into the position shown in Fig. 4. The upward movement 45 of the member 42 causes the arm 44 to close the contacts at 45 and 46. Current then flows from battery B, see Figs. 7, and 8, conductor 47, contacts 45, conductor 48, magnet 31, 49, and by conductor 50 to battery. The armature 31^a of the magnet 31 50 is energized and swings the lever 36 forwardly. The pawl 38 which is in engagement with one of the teeth 21^x pushes the unit which bears it forwardly a distance 55 equal to half the length of the unit. Since adjacent units are connected by means of links 51, see Fig. 5, the whole train of units will be moved forwardly on the track. On the further upward movement of the member 42, the contacts at 46 will be closed, and since the contacts at 40 and 41 have been closed by the movement of the lever 36, current will flow from the battery B, see Fig. 8, through 47, 46, 52, 41, lever 36, 40, 53, magnet 30, and by conductors 50 to

battery. This will energize the magnet 30 which at this stage of the operation, is in retracted position. The armature 30^a will be attracted thereby swinging forwardly the lever 33 and its pawl 35 will engage the tooth 21^y (since the units have been moved forwardly half the distance of the length of one unit), and will cause the movement of the train of units another half length, thus bringing into position a new unit. On release of pressure from the key 5, the member 42 will resume its original position, thereby breaking the contacts at 45 and 46.

It will be seen that the contacts 45 and 46 are closed in succession. The operation 80 of the magnet 30, does not necessarily depend upon the closing of these contacts in succession, but rather upon the closing of the contacts 40 and 41 by the movement of the lever 36, since these latter contacts 85 form part of the circuit of the magnet 30. It will therefore be seen that the magnet 30 will not be energized until after the magnet 31 has been energized. The magnet 31 therefore effects the primary movement of 90 half the length of a unit, while the magnet 30 effects the remaining half of the movement.

When a new unit has been brought into 95 operative position, any number from 0 to 9 may be thrown upwardly into view from said unit by pressing the key corresponding to the number. These numbers will be retained until they engage a roller or bar 54 on the under side of the track, see Figs. 100 1 and 3. At this point, the movement of the train will pass the plates back into position, so as to be engaged by the hook 28^a which will engage the shoulder 24^a on the plate. The members are thus automatically 105 reset, but it will be observed that they will stay in position long enough to enable an operator not only to know whether he has pressed one key correctly, but whether he has pressed a whole series of keys correctly. 110 In Fig. 3 it will be observed that approximately eighteen numbers will remain in view on the upper portion of the track and the curved portion at the left of the figure, before they are automatically reset when 115 they come in contact with the roller 54.

It may be desirable at times to move the train forwardly without displaying any number. To this end I provide an auxiliary key 55 whose operation will close contacts 120 56 and 57, see Fig. 7. These contacts are connected with the contacts, or rather with the conductors leading through the contacts, 45 and 46, so that the operating circuit of both magnets will be closed, with the exception, of course, that the operating circuit of the magnet 30 is not closed until after the operation of the magnet 31. The magnet 31 will therefore operate to cause a half step 125 of the train, and the magnet 30 will there- 130

upon effect the remaining half without displaying the numbers.

It will thus be seen that we have provided a device to work in conjunction with any device provided with a keyboard to indicate that the operations on the keyboard have been correctly performed. The provision of an indicating device in which the indicating elements will remain in position long enough to enable the operator to determine whether or not he had correctly performed a series of operations, forms an important feature of our invention. The provision of a device of the type described in which these numbers after remaining in sight for a sufficient length of time, are automatically reset, also forms another feature.

Another feature to which we desire to call attention is the fact that operation of the device is continuous, that is to say, the operator does not have to reset any of the figures himself, or to stop after a certain length of time and adjust the device for different conditions.

We claim:—

1. The combination with a keyboard having a plurality of keys, of a separate lever associated with each of said keys, and adapted to be operated thereby, a series of units forming an endless chain, each of said units being provided with a series of spring pressed members bearing characters corresponding to those of the complete keyboard, means associated with each of said levers for releasing its corresponding spring pressed member and bringing it into view, and electro-magnetic means for simultaneously moving the endless chain of units to bring another unit into operative relation with the levers.

2. The combination with a keyboard having movable keys, of a series of levers associated with said keys, an endless chain of units, means for supporting said endless chain, each unit comprising a casing having a plurality of spring pressed members normally held inside the casing, said members bearing characters corresponding with those on the complete keyboard, and means associated with each of said levers for releasing one of said spring pressed members and bringing the latter into view.

3. The combination with a keyboard having movable keys, of a series of levers associated with said keys, an endless chain of units, means for supporting said endless chain, each unit comprising a casing having a plurality of spring pressed members normally held inside the casing, said members bearing characters corresponding with those on the complete keyboard, and means associated with each of said levers for releasing one of said spring pressed members and bringing the latter into view, said last-

named means comprising a push rod associated with each lever, and a trip associated with each of said spring pressed members and adapted to be engaged by its individual push rod.

4. The combination with a keyboard having movable keys, of a series of levers associated with said keys, an endless chain of units, means for supporting said endless chain, each unit comprising a casing having a plurality of spring pressed members normally held inside the casing, said members bearing characters corresponding with those on the complete keyboard, means associated with each of said levers for releasing one of said spring pressed members and bringing the latter into view, said last-named means comprising a push rod associated with each lever, and a trip associated with each of said spring pressed members and adapted to be engaged by its individual push rod, and electro-magnetic means for simultaneously moving the endless chain forward at each operation of any of the levers.

5. The combination with a keyboard having movable keys, of a series of levers operatively associated with said keys, an endless chain of units, each unit comprising a casing, a series of spring pressed pivoted plates carried by said casing, each of said plates bearing a character corresponding to one on the keyboard, means including a trip associated with each plate for retaining the plates within the casing, a push rod associated with each lever and adapted to engage its corresponding trip and release a spring pressed plate, thereby permitting the latter to be brought into view by the action of the spring.

6. The combination with a keyboard having movable keys, of a series of levers operatively associated with said keys, an endless chain of units, each unit comprising a casing, a series of spring pressed pivoted plates carried by said casing, each of said plates bearing a character corresponding to one on the keyboard, means including a trip associated with each plate for retaining the plate within the casing, a push rod associated with each lever and adapted to engage its corresponding plate and release a spring pressed plate thereby permitting the latter to be brought into view by the action of the spring, a circuit closer, a movable member actuated by the movement of any of said levers for operating said circuit closer, and means controlled by said circuit closer for moving forward the endless chain of units.

7. The combination with a keyboard having movable keys, of a series of levers operatively associated with said keys, an endless chain of units, each unit comprising a casing, a series of spring pressed pivoted plates carried by said casing, each of said plates

- bearing a character corresponding to one on the keyboard, means including a trip associated with each plate for retaining the plate within the casing, a push rod associated with each lever, and adapted to engage its corresponding plate and release a spring pressed plate thereby permitting the latter to be brought into view by the action of the spring, a circuit closer, and a movable member actuated by the movement of any of said levers for operating said circuit closer, an electro-magnetic device controlled by the circuit closer for moving the endless chain of units forwardly at the operation of any of said levers, thereby bringing a new unit into operative relation with said push rods.
8. The combination with a keyboard having movable keys, of a series of levers operatively associated with said keys, an endless chain or units, each unit comprising a casing, a series of spring pressed pivoted plates carried by said casing, each of said plates bearing a character corresponding to one on the keyboard, means including a trip associated with each plate for retaining the plate within the casing, a push rod associated with each lever and adapted to engage its corresponding plate and release a spring pressed plate thereby permitting the latter to be brought into view by the action of the spring, a circuit closer, a movable member actuated by the movement of any of said levers for operating said circuit closer, a pair of electro-magnets controlled by said circuit closer, and means associated with said magnets for conjointly moving said endless chain of units a predetermined distance.
9. The combination with a keyboard having movable keys, of a series of levers operatively associated with said keys, an endless chain of units, each unit comprising a casing, a series of spring pressed pivoted plates carried by said casing, each of said plates bearing a character corresponding to one on the keyboard, means including a trip associated with each plate for retaining the plate
- within the casing, a push rod associated with each lever and adapted to engage its corresponding plate and release a spring pressed plate thereby permitting the latter to be brought into view by the action of the spring, a circuit closer, a movable member actuated by the movement of any of said levers for operating said circuit closer, a pair of electro-magnets controlled by said circuit closer, means associated with each magnet for conjointly moving said endless chain of units a predetermined distance, and means for causing said magnets to act successively.
10. The combination with a keyboard having a plurality of keys, of a separate lever associated with each of said keys, and adapted to be operated thereby, a series of units forming an endless chain, each of said units being provided with a series of spring-pressed members bearing characters corresponding to those on the complete key-board, means associated with each of said levers for releasing its corresponding spring-pressed member and bringing it into view, and means for simultaneously moving the endless chain of units to bring another unit into operative relation with the levers.
11. The combination with a keyboard having a plurality of keys, of a separate lever associated with each of said keys and adapted to be operated thereby, a series of units forming an endless chain, each of said units being provided with a series of members bearing characters corresponding to those of the complete keyboard, means associated with each of said levers for bringing its corresponding member into view, and means for simultaneously moving the endless chain of units to bring another unit into operative relation with the levers.
